(57) **CLAIM**

The ornamental design for a sprinkler pattern disc, as shown and described.

DESCRIPTION

FIG. 1 is a rear right perspective view of the present new design for a sprinkler pattern disc configured to include an exemplary sprinkler head and sprinkler base which are illustrated in dashed lines and form no part of the claimed design;

FIG. 2 is a rear right perspective view of the present new design for a sprinkler pattern disc;

FIG. 3 is a top plan view thereof;

FIG. 4 is a left elevational view thereof, the right elevational view being a mirror image thereof;

FIG. 5 is a front elevational view thereof;

FIG. 6 is a rear elevational view thereof; and,

FIG. 7 is a bottom plan view thereof.

The broken lines showing various features of a sprinkler pattern are for illustrative purposes only and form no part of the claimed design.
